UNITED STATES PATENT OFFICE.

ERNEST F. ELMBERG, OF PARKERSBURG, IOWA.

POWER-TRANSMISSION ATTACHMENT.

1,271,683.

Specification of Letters Patent.

Patented July 9, 1918.

Application filed December 15, 1917. Serial No. 207,225.

To all whom it may concern:

Be it known that I, ERNEST F. ELMBERG, a citizen of the United States of America, and a resident of Parkersburg, Butler county, Iowa, have invented certain new and useful Improvements in Power-Transmission Attachments, of which the following is a specification.

My invention relates to improvements in power transmission attachments, and the object of my improvement is to supply mechanism of this type of a simple and convenient construction adapted for detachable attachment to the crank-shaft of the motor of a motor-vehicle or other prime-mover, and which shall be capable of transmitting power to driven mechanism with a minimum loss of power. Other objects of my improvements will be more specifically hereininafter described, pointed out in the claims, and illustrated in the accompanying drawings, in which, where similar numerals of reference denote corresponding parts, Fig. 1 is a plan view of my improved power transmission attachment as connected to a driving-shaft; Fig. 2 is a side elevation of the same, more specifically showing the means for adjustably mounting the device on the frame of the prime-mover; Fig. 3 is a fragmental under plan view of the forward end of the device, showing the cam-controlled adjustable clip thereon; Fig. 4 is an end elevation of the releasable ratchet-crank of said device, and Fig. 5 is a detail view, on a magnified scale, of said ratchet-crank, as separated from the driven parts of the device, with parts sectioned or broken away.

Referring to the drawings, in which the numeral 56 denotes the fixed part of the front axle of a motor vehicle, 57 the front cross-connecting bar of the frame thereof, and 1 the forward end of the crank-shaft of the motor thereof, the numerals 30, 31 and 35 denote the rearwardly diverging horizontal frame bars of my device and the spaced cross-plates fastened thereto by bolts 37 and 36 respectively. Bars 49 are fastened by bolts 50 to the tops of the frame-bars 30 to extend rearwardly therefrom and rest upon the top of the cross-connection 57 to support the rear end of the device. Upon the forward cross-plate 35 a pair of bars 44 are secured by means of bolts 43 and may be rocked horizontally for adjusting purposes. On each bar 44 at its rear end is an upright integral lug 45 orificed to receive the for-

ward threaded end of a rod 47 and secured by a nut 46.

The rear end of each rod 47 is downwardly hooked at 48 to hook over the top of 60 said cross-connection 57.

Referring now to said Fig. 2, as also to Fig. 3, the numeral 59 denotes a cross-bar secured on the under face of the forward part of each frame-bar 30 by means of bolts 65 36. Secured medially on said bar 59 by a bolt 61 is a rearwardly extending bar 60, medially twisted to present itself vertically edgewise and sloping downwardly and rearwardly and having a medial longitudinal 70 groove and slot 62 on one side. The numeral 63 denotes a rod whose forward end is bent at a right angle at 64 to pass through the forward part of the slot 62 and secured by a nut to prevent separation from the bar 75 60 while permitting longitudinal movement of said end 64 in said slot. On said end 64 is pivotally mounted a cam 65, whose edge bears movably against the forward wall of an angular lug 70 on the end of the bar 60. 80 Said cam has a handle 66. Another rod-part 68 is connected adjustably to the rod-part 63 in alinement by means of a turn-buckle 67, and has at its rear end an upturned hook 69 adapted to be hooked under 85 the axle-member 56. A channeled brace-bar 52 is connected by means of bolts 53 and 36 at its rear and forward ends to the rear depending parts 51 of the frame-bars 30 and the forward parts of said frame-bars, re- 90 spectively. An adjustable spacing-bar 55 is secured to the rear face of each of the depending parts 51 by means of a screw-bolt 54 to be interposed between the part 51 and the axle-member. 95

A socket 3, see Fig. 5, is secured detachably to the forward end of the driving-shaft 1 by means of a pin 2. Said socket has a diminished hollow shank secured detachably to the rear end of a driven shaft-member 5 by means of a pin 4. On the forward end of said shaft-member 5 is fixed a sleeve 9 carrying a pair of longitudinally alined studs 10 each of cylindrical form. Another sleeve 6 is mounted loosely on the shaft 5 100 and has an enlargement 7 whose forward face is hollowed at 8. Said enlargement 7 has an integral radial arm 11 on which is fixed a crank 13 supplied with a handle 14, and is wide enough to also have secured on 110 its forward face a block 12. The block 12 has a longitudinal hollow 17 and side open-

ing 20 in communication therewith, also an opening on the front face of the block, and said hollow contains a plunger-rod or ratchet-pawl 18, a short coiled compression-spring 16 within said hollow bearing down upon said pawl. A lateral pin 19 on the pawl can rock therewith into or out of the side opening 20 in said block, to thereby fasten the pawl in its upward position, or 10 release it when the pin is rocked forwardly.

The ratchet-crank 13 is intended to be permanently mounted with its carrying-shaft 5 on said driving-shaft 1, and when the frame 30 is removed from the frame of 15 the vehicle, the crank 13 remains, and can be used as a safety crank to crank up said driving-shaft. This is done by sliding the sleeve 6 forwardly on the shaft-member 5 to seat the fixed sleeve 9 partially within the 20 hollow 8 of the enlargement 7, so that the rearmost detent 10 will be positioned to be engaged by the lower end of the pawl 18, when the latter is released and propelled downwardly by said spring 16. This engagement permits rotation of the shafts 5 and 1 by means of the crank 13, but in the event of the engine back-firing the sloping lower end of said pawl rides up over the 25 detent 10, compressing said spring 16, and also pushes back the sleeve 6 to cause the 30 detent to clear the pawl, due to the cylindrical form of the detent. When the frame 30 is mounted on the vehicle to be used as a power transmission attachment thereto, the 35 sleeve 6 may be pushed back out of engagement with the detents, and remain as shown in said Fig. 1, inactive.

When the frame 30 is mounted on the vehicle by the securing-means already described, the fixed sleeve 9 is passed into the axial hollow 23 of the sleeve-part 21 of a universal-coupling composed of the usual parts 24 to 28 inclusive, the pair of detents 10 passing into a key-slot 22. The coupling-member 28 is secured on the rear end 45 of a shaft-member 29 mounted in a pair of spaced bearing-boxes 32 and 41 fixed on said cross-plates 31 and 35 by means of bolts 37 and 36. The boxes have oil-cups 50 33 and 42 respectively, and may contain roller-bearings about said shaft, though this is not essential to my invention. A stop-collar 34 is secured on the shaft 29 intermediate said boxes.

55 Anterior to the frame 30, a belt-wheel 38 is mounted on the shaft 29. The forward end of said shaft has a short longitudinal groove 58 to detachably receive the hooked end of a removable crank 39 provided with 60 a handle 40, for starting purposes when such power attachment is in use. A belt may be run from the belt-wheel 38 to drive any kind of machinery as desired.

It will be seen that this device may be 65 quickly attached to or dismounted from a

vehicle, and that the universal coupling connection therein permits considerable play between the coupled shaft parts as may be necessitated in the operation of adjusting the device in mounting it up or in 70 locating the belt-wheel in a desired plane relative to the machinery driven. The incorporation of the releasable crank 13 also renders the device more convenient, and is always adapted for use by the dismounting 75 of the attachment frame only.

It is intended that this invention cover any of the usual mechanical equivalents, and that various minor changes may be made without departing from the principle 80 of the invention.

Having described my invention, what I claim as new, and desire to secure by Letters Patent, is:

1. In combination, a driving-shaft, a 85 driven shaft element mounted on said driving-shaft, engaging-means on said driven shaft element, a crank mounted loosely and longitudinally slidably on said driven shaft element, and a yieldable resiliently-controlled pawl engaging said engaging-means detachably and mounted on said crank, to rotate the shafts when the crank is rotated in one direction only.

2. In combination, a driving-shaft, a 95 driven shaft element mounted on said driving-shaft, engaging-means on said driven shaft element, a crank mounted loosely and slidably on said driven shaft element, and a yieldable resiliently-controlled pawl 100 mounted on said crank and engaging said engaging-means when the crank is first moved longitudinally in one direction and then rotated in one direction, said pawl riding back over said engaging-means when 105 the connected shaft elements are rotated in a reverse direction and also yielding longitudinally reversely to prevent rotation of the crank when the shafts are reversely rotated.

3. In combination, a driving-shaft, a driven shaft element mounted on said driving-shaft, engaging-means on said driven shaft element consisting of a cylindrical detent on said element, a crank mounted 115 loosely and slidably on said driven shaft element, and a yieldable resiliently-controlled pawl mounted on said crank and engaging said detent when the crank is first moved longitudinally on its shaft in one direction and secondly rotated in one direction, said pawl having a sloping engaging end adapted when the shaft is reversely rotated to ride yieldingly over and off the detent and move backward with the crank to 125 prevent rotation of the crank by the reversed rotation of the shaft.

4. In combination, a driving-shaft, a driven shaft element mounted thereon, another driven shaft element, a universal 130

- coupling detachably connected between said driven shaft elements, a frame on which said second-mentioned driven shaft element is rotatably mounted, a frame on which said 5 driving-shaft is rotatably mounted, adjustable supporting connections between said frames, the first-mentioned driven shaft element having engaging-means adapted to detachably secure it to said universal-coupling, 10 a crank loosely slidably mounted on the first-mentioned driven shaft element and having a yieldable resiliently-controlled pawl mounted thereon and adapted to engage the said engaging-means when the universal-coupling 15 is removed, and the crank moved forward longitudinally on the shaft, to rotate the connected shaft elements in one direction.
5. In combination, a driving-shaft, a 20 driven shaft element mounted thereon, another driven shaft element, a universal coupling detachably connected between said driven shaft elements, a frame on which one of said driven shaft elements is rotatably 25 mounted, a frame on which said driving-shaft is rotatably mounted, adjustable supporting connections between said frames, the first-mentioned driven shaft element having a cylindrical detent thereon, a crank loosely 30 mounted on the first-mentioned driven shaft element, a resiliently-controlled pawl mounted movably on said crank to engage said detent when the crank is rotated in one direction, after the universal-coupling 35 has been uncoupled from said element, to rotate said element in one direction, said pawl yieldably riding over said detent when the said shaft element is rotated in a reverse direction.
- 40 6. In combination, a driving-shaft, a frame on which said driving-shaft is rotatably mounted, an axle supporting said frame, a driven shaft element mounted on said driving-shaft, another driven shaft ele-

ment, a universal-coupling detachably connecting said driven shaft elements, a frame on which said second-mentioned driven shaft element is rotatably mounted, adjustable clips mounted movably on the last-mentioned frame and having engaging-means 45 adapted to releasably engage the first-mentioned frame, the rear end of the last-mentioned frame being supported on the first-mentioned frame, and an adjustable clip 50 movably mounted on the last-mentioned frame and having engaging-means adapted to releasably engage said axle, the rear part of the last-mentioned frame being bent 55 downwardly and engaging said axle.

7. In combination, a driving-shaft, a 60 frame on which said driving-shaft is rotatably mounted, an axle supporting said frame, a driven shaft element mounted on said driving-shaft, another driven shaft element, a universal-coupling detachably connecting said driven shaft elements, a frame on which said second-mentioned driven shaft element is rotatably mounted, adjustable 65 clips mounted movably on the last-mentioned frame and having engaging-means adapted to releasably engage the first-mentioned frame, the rear end of the last-mentioned frame being supported on the first-mentioned frame, an adjustable clip movably mounted on the last-mentioned frame 70 and having engaging-means adapted to releasably engage said axle, the said clip being formed of two parts, a turn-buckle adjustably connecting said parts, said last-mentioned frame having engaging-means, and 75 a cam mounted on the last-mentioned frame to rock thereon in moving engagement with said engaging-means, said cam having a pivotal connection to one of the parts of the last-mentioned clip. 80

Signed at Waterloo, Iowa, this 6th day of Dec. 1917.

ERNEST F. ELMBERG.
